UNITED STATES PATENT OFFICE.

HENRY A. SCHRAMM AND JACKSON D. HAWKINS, OF SAN ANTONIO, TEXAS.

MEMORANDUM-CALENDAR.

1,374,239.

Specification of Letters Patent.

Patented Apr. 12, 1921.

Application filed June 11, 1920. Serial No. 388,094.

To all whom it may concern:

Be it known that we, HENRY A. SCHRAMM and JACKSON D. HAWKINS, citizens of the United States, residing at San Antonio, in 5 the county of Bexar and State of Texas, have invented certain new and useful Improvements in Memorandum-Calendars, of which the following is a specification.

This invention relates to calendars of that 10 sort in which a pad of leaves is provided for exhibiting the calendar information and for receiving memoranda. In such calendars the pad has a number of leaves equal to the number of days in the year and each 15 leaf is printed with calendar information relating to a particular date and has space for receiving memoranda associated with such dates.

The object of the present invention is to 20 provide a memorandum calendar pad of the class described which may be used for two consecutive years. This is accomplished by having the days of one year progressively numbered upon one side of the leaves while 25 the days of the next following year are numbered in reverse order upon the other side of the leaves and thus after all the leaves have been turned for the former year the calendar may be turned around and used 30 for the succeeding year.

Another object of the invention is the production of a simple and efficient filing wire for engaging the calendar leaves, means being provided whereby this filing wire may 35 be easily attached to and detached from the stand.

A still further object of the invention is to generally improve upon memorandum calendars of this character by providing a 40 device which will be extremely simple, durable and inexpensive in construction, one which is efficient and reliable in operation and well adapted for the purpose for which it is designed.

45 With these and numerous other objects in view, the invention resides in certain novel features of construction, the combination and arrangement of parts, as will be hereinafter fully described and claimed.

50 In the accompanying drawings:

Figure 1 is a side elevation of our invention,

Fig. 2 is a top plan view thereof,

Fig. 3 is a section taken on the line 3—3 55 of Fig. 2,

Fig. 4 is a plan view of one side of a leaf of the memorandum calendar,

Fig. 5 is a plan view of the reverse side of the leaf as shown in Fig. 4, and

Fig. 6 is a section taken on the line 6—6 60 of Fig. 3.

Calendars of the form provided by the invention will commonly be used upon the desk. For such use they are conveniently supported upon a holder such as indicated 65 generally by the numeral 10. This holder 10 includes the slanting tables 11 which are spaced from each other so as to provide the opening 12 in which is situated the block 13. This block 13 is supported by the side 70 walls 14 and is provided with the slanting upper surfaces 15 which are in alinement with the tables 11. A perforation extends centrally and transversely through the block 13 for receiving the bolt 16 which is provided 75 with a head on one end and threads for receiving the thumb-nuts 17. By referring to Fig. 6 of the drawing it will be seen that one side of the block 13 is provided with the U-shaped groove 18 which has its 80 fully below the perforation which receives the bolt 16. The other side of the block 13 is provided with two vertical grooves which correspond to the legs of the U-shaped groove 18 in the other side of the 85 block.

A filing wire is carried by the block 13 and consists of the arches 20 which are formed from a single strand of wire and connected at one end by means of the connection 21 and the corresponding legs of the filing wire sit within the U-shaped slot 18 while the other legs are situated within the vertical slots provided on the other side of the block 13. In order to hold this filing 90 wire in place there is provided the strips 23 and 24 which are held in place by means of the bolt 16 and nut 17 as is clearly shown in Figs. 2 and 3 of the drawing. When it is desired to place the leaves upon the filing 95 wire it will be readily seen that it will only be necessary to remove the nut 17 from the bolt 16 and the strip 24 may then be removed so that the connection 21 may be removed from under the bolt 16 and thus the 100 filing wire may be lifted from engagement with the block 13 and the leaves 25 may be threaded or filed upon the filing wire, these leaves 25 being provided with the usual perforation 26. As shown in Fig. 1 the leaves 110

25 in the beginning of the first year are situated upon one of the tables 11 and are marked in a manner so that when all the leaves are turned upon the other table the 5 first leaf will indicate the first day of the succeeding year, et cetera. For example, by referring to Figs. 4 and 5 of the drawing, it will be seen that in Fig. 4, January 1, 1920 is shown and upon the reversed side 10 of this leaf there will be, as shown in Fig. 5, December 31, 1921, or the last day of the succeeding year. Of course the next leaf would have January 2, 1920, and upon its reverse side December 30, 1921, et cetera.

15 From the foregoing description, taken in connection with the accompanying drawing, the construction and operation of the device will be readily understood without a more extended explanation. As numerous 20 changes in form, proportion, and in the minor details of construction may be resorted to without departing from the spirit of this invention, we do not wish to be limited to the construction herein shown 25 and described other than is claimed.

Having thus described our invention what we claim as new is:

1. In a device of the class described the combination of a pair of slanting tables

having a space therebetween, a block carried within said space, a bolt passing transversely through said block, strips carried by said bolt, a wire file carried between said block and said strips.

2. In a device of the class described the combination of a pair of slanting tables situated so as to provide a space therebetween, a block mounted within said space, a wire file carried by said block, and strips engaging said file so as to hold same on said block. 35

3. In a device of the class described the combination of a pair of tables having a space therebetween, a block situated within said space, one side of said block provided with a U-shaped groove, the other side of 40 said block provided with a pair of vertical grooves, a file adapted to be received in said grooves, a bolt passing transversely through said block, strips carried by said bolt so as to hold said file within said groove. 45

In testimony whereof we affix our signatures in presence of two witnesses.

HENRY A. SCHRAMM.
JACKSON D. HAWKINS.
